Inventor

Louis J. Parsons.

LOUIS J. PARSONS, OF NEW BEDFORD, MASSACHUSETTS.

Letters Patent No. 83,201, dated October 20, 1868.

IMPROVEMENT IN THE MODE OF BINDING THE EDGES OF REIN-HOLDERS.

The Schedule referred to in these Letters Patent and making part of the same.

To all whom it may concern:

Be it known that I, LOUIS J. PARSONS, of New Bedford, in the county of Bristol, and State of Massachusetts, have invented a new and improved Mode of Binding the Edges of "Rein-Holes" in "carriage-boots" and horse-blankets, and securing a flap to the former; and I do hereby declare that the following is a full and exact description thereof, reference being had to the accompanying drawings, and to the letters of reference marked thereon.

My invention consists in a metallic frame with flanges, for binding the edges of "rein-holes," to prevent the holes from tearing out at the corners, and a clasp on the top of the face of the frame, by which to secure the flap covering the front of "rein-hole."

Figure 1 is a perspective view of a portion of a carriage-boot having my invention applied, and shows the manner of attaching the flap.

Figure 2 is a view of frame ready to be applied.

Figure 3 is a back view of a portion of a carriage-boot, with frame applied to the "rein-hole."

Fig. 1. A¹ is a portion of a carriage-boot; B¹ is the frame; C. is the flap for covering the front of "rein-hole;" D, clasp for securing the flap to the frame.

Fig. 2. B² is the frame; D², clasp for securing flap; E² E³, flanges for binding and securing frame to boot.

Fig. 3. A³, portion of carriage-boot; C³, flap; E³ E³

E³ flanges bent over, binding the edges of "rein-hole," and securing the frame to the boot.

To apply the frame, the flanges are passed through the hole and turned over the edges; the top edge of the flap placed in the clasp, which is firmly compressed upon it.

The above invention being made and applied as shown, its advantages may be plainly seen. It is simple in construction, easily and quickly applied, and will effectually prevent the "boot" from being torn at the corners of the "rein-hole," a fault so common and troublesome in the old manner of binding. It will also be cheaper and more ornamental than the old method.

Claim.

What I claim as my invention, and desire to secure by Letters Patent, is—

The metallic frame B² for binding the edges of "rein-holes" in carriage-boots and horse-blankets, and securing the flap which covers the front of rein-hole in boots, made and applied substantially in the manner shown and described.

LOUIS J. PARSONS.
